UNITED STATES PATENT OFFICE.

GEORGE TRULOCK, OF LOS ANGELES, CALIFORNIA.

LID HOLDER FOR CONTAINERS.

Application filed November 30, 1927. Serial No. 236,682.

This invention relates to closure fasteners, and more especially to a fastener for preventing the cover of a coffee-pot or similar article, from falling off when tilted.

5 An object of the invention is the provision of means for retaining the cover or lid of a receptacle in place when the receptacle is tilted for the purpose of pouring its contents therefrom; the retaining means being of such 10 a nature that it may be moved to retaining position by simply compressing a trigger provided for that purpose in the handle of a receptacle, so that the normal use of the receptacle is not made more complicated.

15 Another object is the provision of a cover retaining device of the above described nature, which does not detract from the attractiveness of the receptacle to which it is applied.

20 With the foregoing and other objects in view which will be made manifest in the following detailed description and specifically pointed out in the appended claims, reference is had to the accompanying drawings for an 25 illustrative embodiment of the invention, wherein:

Figure 1 is a perspective view of a coffee-pot having the lid retaining device incorporated therewith.

30 Fig. 2 is a side elevation of the handle of the coffee-pot of Figure 1, and lid retaining device. Portions are broken away to reduce the size of the Figure.

Fig. 3 is a sectional view, the plane of section being indicated by the line 3—3 of Figure 1.

35 Fig. 4 is a sectional view of a portion of a coffee-pot or other handle having a modified form of my holder incorporated therewith.

40 Fig. 5 is a sectional view of a portion of a handle with another modification of my holding device incorporated therewith.

Referring to the accompanying drawings 45 wherein similar reference characters designate similar parts throughout, the preferred embodiment of my invention is shown incorporated with a coffee-pot 1 having a lid 2, lip 3, and handle 4. In most coffee-pots of 50 the type illustrated, the lid is apt to fall from the pot when the contents of the pot are being poured therefrom; and it is a purpose of my invention to prevent this. For this purpose, I have provided a detent 6 bent 55 at its upper end to provide a hook 7 adapted to extend over the edge of the lid 2, and piv-

oted at its lower end 8 within a groove 9 in that part of the handle 4 facing the coffee-pot 1. The groove 9 is of sufficient size to receive substantially all of the detent 6 when 60 it is laid back against the handle 4 as illustrated in Figures 1 and 2.

A trigger 11 is pivotally mounted within a recess 12 in the upper surface of the handle 4 in a position where it may be conveniently engaged by the thumb of the person using the coffee-pot when pouring the contents therefrom. A spring 13 compressed between the trigger 11 and handle 4, urges the free end of the trigger upwards. 70

A rod 16 is pivoted at one end to the trigger 11, and at the other end to the detent 6 extending through a hole 17 in the handle 4. The proportionate arrangement of the parts is such, that when the trigger 3 is depressed 75 into the recess 12 as shown in Figure 3, the rod 16 will push the detent 6 into its engaging position so that the cover 2 will be held in place while the coffee-pot 1 is tilted. When the trigger 11 is released, the spring 13 will 80 urge it upwards, exerting tension upon the rod 16, and pulling the detent 6 back into the groove 9 to release the lid 2.

It is therefore seen that the lid holder of my invention in no way interferes with 85 the normal use of the coffee-pot. The lid may be removed or replaced without interference from the lid holder; but when the operator wishes to pour the contents of the coffee-pot 1, he has merely to grasp the handle 90 4 in the usual manner, and with his thumb upon the trigger 11. The natural grip of the user will depress the trigger and force the detent 6 into the lid engaging position. In view of the fact that practically all of 95 the device is concealed within the handle 4 when not in use, it does not detract from the normal attractiveness of the receptacle 1.

In the modified form of my invention as shown in Figure 4, the detent 6 is operated 100 in a similar fashion by the rod 16 which is pivoted to a trigger 21. This trigger 21 differs from that previously described, in that it is provided adjacent its pivoted end with a projecting lug 22 to which the upper 105 end of the rod 16 is pivoted. With this type of trigger a smaller amount of movement of the trigger 21 is required to produce the same amount of movement of the rod 16 and detent 6. The spring used beneath the trigger 21 may be of any convenient type, but I 110 have found a flat bent strip 23 of spring metal

as shown in Figure 4, to be altogether satisfactory.

The modification shown in Figure 5 comprises a detent 6 and trigger 21 pivoted within the handle 4 as previously described. Instead however, of having the rod 26 pivoted at one end to the detent 6 and at the other to the trigger 21, it is slidably mounted within the aperture 17 in the handle 4, with one end abutting 10 against the detent 6 and the other against the lug 22 of the trigger 21. An additional spring 27 preferably mounted upon the handle 4, has its free end 28 bearing against the detent 6 to urge it back against the handle 4 to cover-releasing position. In this type of device, when pressure is relieved from the trigger 21, the spring 23 will urge it upwards and the spring 27 will urge the detent 6 and rod 26 into the position indicated in Figure 5. A flange 29 extends from the outer end of the trigger 21 to engage a complementary flange 31 on the handle 4 to limit the upward movement of the trigger 21.

It will be understood that various changes 25 in the details of construction may be made without departing from the spirit or scope of the invention as defined by the appended claims.

I claim:

30 1. In combination with a receptacle having a cover and a handle, a detent pivoted within a groove in said handle and adapted to be extended therefrom to engage said cover, a trigger pivotally mounted within a recess in the top of said handle, said trigger being substantially complementary in shape to said recess, a rod extending through a hole in said handle and pivoted at one end to said detent above the pivotal mounting thereof, and pivoted at the other end to said trigger, said rod being adapted to extend the detent to its engaging position when the trigger is depressed, and a spring interposed between the trigger and handle for urging the detent to releasing position.

50 2. In combination with a receptacle having a cover and a handle, a detent pivoted within a groove in said handle and adapted to be extended therefrom to engage said cover, a trigger pivotally mounted within a recess in said handle, said trigger being substantially complementary in shape to said recess, a rod extending through a hole in said handle and pivoted at one end to said detent above the pivotal mounting thereof, and pivoted at the other end to said trigger, said rod being adapted to extend the detent to its engaging position when the trigger is depressed, and a spring interposed between the trigger and handle for urging the detent to releasing position.

3. In combination with a receptacle having a cover and a handle, a detent pivoted within a groove in said handle and adapted to be extended therefrom to engage said cover, a trigger pivotally mounted within a recess in said handle, a rod extending through a hole in said handle and pivoted at one end to said detent above the pivotal mounting thereof, and pivoted at the other end to said trigger, 65 said rod being adapted to extend the detent to its engaging position when the trigger is depressed, and a spring interposed between the trigger and handle for urging the detent to releasing position. 70

4. In combination with a receptacle having a cover and a handle, a detent pivoted within a groove in said handle and adapted to be optionally extended therefrom to engage said cover or withdrawn to release the cover, a trigger pivotally mounted within a recess in said handle, a rod mounted for movement within the handle and operatively connecting the trigger and detent, said rod being adapted to extend the detent to its engaging 80 position when the trigger is depressed, and a spring interposed between the trigger and handle for urging the detent to releasing position. 85

5. In combination with a receptacle having a cover and a handle, a detent pivoted to said handle and adapted to be optionally extended therefrom to engage said cover or withdrawn to release the cover, a trigger pivotally mounted on said handle, a rod operatively connecting said trigger and detent and adapted to extend the detent to its engaging position when the trigger is depressed, and a spring interposed between the trigger and handle for urging the detent to releasing position. 90

6. In combination with a receptacle having a cover and a handle, a detent pivoted to said handle and adapted to be optionally extended therefrom to engage said cover or withdrawn to release the cover, a trigger pivotally mounted on said handle, a rod operatively connecting said trigger and detent and adapted to extend the detent to its engaging position when the trigger is depressed, and means for urging the detent to its releasing position. 105

7. In combination with a receptacle having a cover and a handle, a detent pivoted to said handle and adapted to be optionally extended therefrom to engage said cover or withdrawn to release the cover, a trigger pivotally mounted on said handle, and a rod operatively connecting said trigger and detent and adapted to operate the detent. 115

In testimony whereof I have signed my name to this specification.

GEORGE TRULOCK.
